UNITED STATES PATENT OFFICE.

AUGUSTIN VICTOR ANDRÉ BOURDON, OF PARIS, FRANCE.

REMOVABLE GAS-BURNING DEVICE FOR HEATING DOMESTIC STOVES.

Application filed May 21, 1923. Serial No. 640,592.

To all whom it may concern:

Be it known that I, AUGUSTIN VICTOR ANDRÉ BOURDON, citizen of the French Republic, residing at Paris, Seine, France, have invented new and useful Improvements in Removable Gas-Burning Devices for Heating Domestic Stoves, of which the following is a specification.

The object of the present invention is a gas burning device providing for the complete heating of any domestic stove in which a solid fuel is usually burnt, without it being necessary to bring any constructional modification to said stove.

A characteristic feature of the apparatus according to the invention resides in that it comprises a main support whereupon an upper burner and a central support are secured, while two lower burners adjustably supported by said central support are adapted to be disposed within the fire pot of the stove with which the apparatus is used, the air necessary for the combustion of all said burners being supplied by the usual draught of the stove.

Said apparatus may thus be placed on the stove or removed from the latter, without any preliminary dismounting and the stove may again be heated with solid fuel at any moment, if desired.

In the accompanying drawings which show by way of example an embodiment of the invention:

Figure 1 is an axial section of the burner on line A—A (Fig. 2).

Figure 2 is partly a section on line B—B (Fig. 1) and partly a plan view.

Figure 3 is a section on line C—C (Fig.

1), the lower burners being shown in plan view; in said figure two positions which may be taken by the burners are shown in full lines and in full and dotted lines respectively.

In the apparatus shown in the drawings, 1 is a ribbed cast iron base which receives the support 2. These two pieces are connected together by two screws 3 (Fig. 2). Within the support 2 is mounted the upper burner 4 provided with the cover 5 (of cast iron) having the holes 6. The burner 4 is supported by the base 1 by means of a lug 7.

A grate 8 and two flat rings 9 and 10 as well as a lid 11 (Fig. 1), are placed upon the support 2, all these members being

preferably of cast iron. The rings and the lid close the top opening of the support 2.

A cast iron guide piece or sleeve 13 is also secured by two screws 12 to the support 2 and a cast iron sleeve 14 held by a screw 15 is adapted to slide inside the guide 13. Two elbows 16 and 16^a are fixed to the support 1 and are connected on the one hand through the medium of the tube 17 with the cock 18 and on the other hand through the medium of the tube 19 with the elbow 20. Upon this elbow 20 is screwed tight a threaded tube 21 upon which a T-shaped member 22 may be displaced vertically by screwing or unscrewing. Upon this T-piece 22 two like lower burners are rotatably supported by means of the plugs 23, each burner comprising a cast iron pipe 24 secured to the plug 23 by means of a screw 25 and a nut 26 holds the pipe 24 in position. The nut 26 is hollow and constitutes an injector which may be regulated as to feed by the screw-needle 27.

To each pipe 24 is attached a cast iron ring 28 in which is mounted a perforated crescent-shaped element 29, the whole being held by the screw 30. The portion 28—29 may pivot on the screw 30, if desired.

A coupling elbow 31 is secured to the support 2 by a nut 33 provided with a central hole 34 and constituting also an injector (Fig. 2). At 34^a is a regulating screw-needle. The elbow 31 is connected by another elbow 35 with the cock 36. The cocks 18 and 36 are screwed to a supply tube 37 which is closed at one end by a plug 38 and connected at the other end to a hose coupling 39, for instance by two elbows 40 and 41 and a tube 42.

The cocks 18 and 36 are each controlled by a rod 43 provided with an insulating handle 44, which obviates all direct contact with the cocks which are heated by conduction. The rods 43 are each guided on a pivot piece 50 rotatably mounted on the supply tube 37.

The operation is as follows: The apparatus being inserted through the usual upper openings of the stove to be heated, the support 1 lies upon the upper plate of the stove in lieu of the rings and lid which usually close said openings, and the burners 29 are thus disposed within the fire pot of the stove. The gas admitted through the hose-coupling 39 enters the tube 37 and flows

through the cocks 18 and 36 either to the upper burner 4 or to the two lower burners 29.

The gas flowing through the cock 36 reaches the central injector 34 of the nut 23 and is injected into the burner 4, drawing in primary air coming from the outside and passing through an orifice 45 in the support 2. The secondary air required for the combustion of the gas discharged by the burner 4 comes from the ash pit of the stove and passes through the sleeves 14 and 13. The mixture of air and gas is discharged through the holes 6 and the flames come directly into contact with any article laid on the grate 8 or on the set of rings and lid 9, 10, and 11. The grate 8 allows the hot gases to flow around an article to be heated whose diameter is less than that of the grate. Notches 15 are formed at 46 around the top edge of the support 2 in order to facilitate the circulation of the hot gases when the article to be heated has a greater diameter than that of the apparatus.

The gas, flowing through the cock 18, passes through the tubes and elbows 17, 16, 16^a, 19, 20, 21, 22 and then through the plugs 23, and reaches the two injectors 26. When issuing from each injector, the gas is mixed 30 with the air coming from the ash-pit of the stove and the combustible mixture, escapes through the crescent-shaped burners 29. The flames are distributed through the notches 47 provided in the burners 29. Said flames 35 heat the walls of the fire pot, in the same manner as with the coal when coal is burned in the stove. The hot burnt gases produced by the combustion of the combustible mixture are thus caused to follow the same path 40 as the gas produced by the combustion of coal, and the whole stove is thus heated, the draught of the stove being used for the combustion of coal. Moreover the secondary air required for the combustion of the 45 lower burners coming from the ash pit, is heated by the contact with said burners and the excess of said air circulates with the hot burnt gases produced by the combustion. This circulation may be regulated by acting 50 on the draught of the stove.

The couplings 40 and 41 for the gas feed may be turned in any convenient direction, and the same may as well be placed in place of the plug 38 according to the requirements 55 of the stove installation.

Figure 3 shows the arrangement of the burners 29 upon the plugs 23. These latter are caused to rotate with the pipes 24, and the holes of the injectors 26 remain thus 60 constantly on the axis of the conduits of the pipes 24 in spite of this rotation. This device permits of placing the two burners in any position with respect to each other. Each burner may be rotated in a position 65 comprised between that shown in full lines

in Fig. 3 and that shown in full and dotted lines in this same figure at 29^a. These positions of the burner will be of course in accordance with the width of the fire pot and in such manner that the flames shall always 70 be in contact with the walls of the latter.

By unscrewing the screw 15 (Fig. 1) and screwing or unscrewing the piece 22, the burners 29 may be raised or lowered according to the depth of the fire pot in which the 75 removable apparatus is disposed.

The injectors are adjustable according to the pressures or according to the desired outputs, by the use of the needle valves 27 and 34^a.

The apparatus according to the invention is very efficient and also of a hygienic use since the discharge of the burnt gases is effected through the chimney of the stove.

Having now described my invention what I claim as new and desire to secure by Letters Patent is:

1. A gas burning device comprising a support, an upper burner carried by said support, means for supplying gas to said upper burner, a central vertical pipe depending from said support, lower burners carried by said pipe at the lower end thereof and in communication therewith, and means for changing the length of said pipe whereby the vertical distance between said upper and lower burners may be adjusted.

2. A gas burning device comprising a support, an upper burner carried by said support, means for supplying gas to said upper burner, a central pipe secured to said support and below the same, a hollow T-shaped member screwed on the lower end of said central pipe, two plugs rotatably mounted on the ends of the cross part of said member and provided with an axial bore, a lower burner secured to each of said plugs and in communication with the axial bore of the latter and means for supplying gas to said central pipe.

3. A gas burning device comprising a support, an upper burner carried by said support, means for supplying gas to said upper burner, a central pipe secured to said support and below the same, a hollow T shaped member screwed on the lower end of said central pipe, two plugs rotatably mounted on the ends of the cross part of said member and provided with an axial bore, a lower burner secured to each of said plugs and comprising a pipe open at its lower part and in communication with the axial bore of the plug and a perforated burner cap pivotally supported by said pipe, and means for supplying gas to said central pipe.

4. A gas burning device comprising a support, an upper burner carried by said support, means for supplying gas to said upper burner, a central pipe secured to said support and below the same, a hollow T shaped

- member screwed on the lower end of said central pipe, two plugs rotatably mounted on the ends of the cross part of said member and provided with an axial bore, a lower 5 burner secured to each of said plugs and in communication with the axial bore of the latter, a sleeve of adjustable length carried by said support and surrounding said central pipe and T-shaped member, said sleeve 10 opening below the upper burner.
5. A gas burning device comprising a support, an upper burner carried by said support, means including an adjustable needle valve for supplying gas to said upper burn- er, a central pipe secured to said support 15 and below the same, a hollow T-shaped member screwed on the lower end of said central pipe, two plugs rotatably mounted on the ends of the cross part of said member and provided with an axial bore, a lower 20 burner secured to each of said plugs and in communication with the axial bore of the latter through the intermediary of an adjustable needle valve and means for supplying gas to said central pipe. 25

In testimony whereof I have signed my name to this specification.

AUGUSTIN VICTOR ANDRÉ BOURDON.
